Application November 9, 1935, Serial No. 49,007

6 Claims. (Cl. 101—93)

This invention relates to printing mechanism and more particularly to printing mechanism of the record card controlled type arranged for the printing of alphabetic information. The record cards from which alphabetic or other data are obtained are generally divided into fields, each comprising a definite predetermined number of information receiving columns. When alphabetic information, such as names of persons or commodities, is entered into such fields of fixed extent, the number of columns utilized in recording the information is dependent on the particular name. Thus, if a record card is arranged with a field to receive surnames and a separate field to receive first names, and if the two fields are adjacent, the space between the two names would vary according to the length of the name in the first field. In printing under control of these record cards, the spacing necessary to provide for the possible printing from all columns in the fields would also result in a varied spacing between the surname and first name which would vary as the length of the surname, if the latter is printed before the first name, or would vary as the length of the first name and middle initial, if such are to be printed before the last name.

It is accordingly the principal object of the invention to provide means for printing a succession of names with a normal space-relationship where the record card from which the names are derived may contain the same with an abnormal spacing between them.

A more specific object of the invention is to provide a shifting device between the record card sensing mechanism and the columns of printing devices of the tabulating machine to cause surnames and first names to be printed with a normal spaced relationship.

A further object of the invention is to provide means for permitting the printing of surnames and related first name in normal order or in reverse order and maintaining them in normal spaced relationship for either order.

Various other objects and advantages of the invention will be obvious from the following particular description of one form of mechanism embodying the invention or from an inspection of the accompanying drawings; and the invention also constitutes certain new and useful features of construction and combination of parts herein-after set forth and claimed.

In the drawings:

Fig. 1 is a transverse sectional view through a typical printing mechanism to which the present invention may be applied.

Fig. 2 is a wiring diagram of the electric circuits necessary for carrying out the invention.

Fig. 3 is a representation of a record card having fields of fixed extent in which names may be entered in the form of perforations. 5

Fig. 4 is a specimen of a printed record card in which the surname precedes the first name and initial.

Fig. 5 is a further specimen of a printed record in which the first name and initial precede the surname. 10

Fig. 6 is a chart showing the timing relation of certain of the controlling contact cams.

In Fig. 3 is shown a record card having two fields headed "Surname" and "First name", in each of which various names may be entered in the form of perforations and it will be appreciated that more, or less, columns will be utilized in each field according to the particular name entered therein. It will be appreciated that in place of surnames and first names, the entries may represent names of commodities and descriptive information. In usual tabulating practice, an entire field, such as that headed "Surname" is connected to a bank of printing type bars equal in number to the number of columns contained in the field and the second field is similarly connected to another bank of type bars. If these banks are adjacent one another, it is obvious that printing will take place with spacing between the two names, which is dependent upon the number of unused columns in one of the fields. For example, for the card illustrated in Fig. 3, where fifteen columns are allotted to the "Surname" and ten columns to the "First name", if printing is to take place with the surname preceding the first name, it will appear as follows:

Doe . . . . . John T.

This separates the two names by twelve spaces. 40 For another record with the name Richard M. Campbell, the printing would appear as follows:

Campbell . . . . . Richard M.

This will give seven spaces between the names. 45 This form of printed record is frequently undesirable and the mechanism to be described hereinafter will point out how the variable spacing between names is changed to a constant single space.

Before explaining the specific manner in which this is brought about, a brief explanation will be given of the printing mechanism to which the invention has been applied. This printing mechanism is the same as that shown and described 55

in Patent No. 1,947,259, granted February 13, 1934, to A. E. Gray.

A vertically reciprocable crosshead 10 (Fig. 1) is suitably guided for up and down movement and carries group selector bars 11 therewith which, in turn, are vertically shiftable on the crosshead 10 and held in the position shown with respect thereto by springs 12. Each bar is provided with teeth 13 corresponding in number 10 and arrangement to the twelve index point positions on the record card (Fig. 3). The upward movement of crosshead 10 is synchronous with the movement of the perforated cards through the machine so that as the index point 15 positions 9, 8, 7, 6, etc. successively pass the analyzing brushes, the corresponding teeth 13 of bar 11 successively, and in the same order, pass the nose of the pawl 14 carried by type bar 15. The crosshead 10 slows down near the end of its upward movement so that the more closely spaced teeth at its lower end pass pawl 14 as the corresponding index point positions 0, 11, and 12 of the card are analyzed. The pawl 14 is normally latched in position out of the path of teeth 13 20 and energization of a magnet 16 will release the pawl for engagement with one of the teeth 13 whereupon the type bar 15 will be picked up and carried along with the crosshead 10. In this manner the type bar is coupled to the crosshead 25 and moved upwardly thereby to present the type element 17 corresponding to the tooth 13 engaged by pawl 14 to the printing line of the platen 18.

In this manner any numeral or other character represented by a single index point perforation in a card column may be selected for printing, the particular one selected depending on the index point perforated in the card column. Where alphabetic characters are to be printed, a magnet 16 is energized under control of the 30 so-called zone perforations in the 0, 11, or 12 index point positions and the circuits are arranged so that the magnet 16 is responsive to perforations in the 9 to 1 positions, while the magnet 18 is responsive to the remaining positions.

The operations involved in selecting an alphabetic character for printing may best be understood by tracing a particular example. Assume the character identified by characters in the 6 and 11 index positions of the card column. As this column traverses the analyzing brushes, crosshead 10 is rising synchronously therewith. At 6, magnet 16 is energized, coupling type bar 15 to crosshead 10. Crosshead 10 continues its up-stroke as the card continues to traverse the brushes. At 11, magnet 19 is energized causing interception of type bar 15 through the tripping of pawl 20 and with it bar 11, stopping the latter two steps or type positions before the 6 type 40 reaches the printing line, thus presenting the "0" type for printing. Had magnet 19 been energized at 12, the type bar would be stopped one step before the 6 type position and if the magnet 19 were not energized at all, type bar 15 would advance to the limit of stroke of crosshead 10 to present the 6 type to the printing line.

The circuits for controlling the magnets 16 and 19 in accordance with the disclosure in the patent referred to are shown in Fig. 2. As the card passes the usual lower analyzing brushes 18, circuits are completed from one side of line 21, through cam contacts T4, T5, which are closed only during the passage of the card by the brushes, lower card lever contacts LCL, a distributing commutator 23, to the common con-

ducting roll 24, thence through the perforations in the card to plug sockets 25. From plug sockets 25 a plug connection is made to a socket 26 and another connection is made from the same socket 25 to a plug socket 27 associated with the same type bar to whose socket 26 a connection has been made. The circuit to the magnet 19 is then traceable from the socket 25 through connection to socket 26 to the associated wire 28, brushes 29 of a commutator 30, through a wire 10 31 to magnet 19 and thence through a commutator 32 to the other side of line 33. The commutators 30 are arranged to electrically connect their brushes 29 during the transit of the index point positions 0, 11, and 12 past the lower 15 brushes and to open such connection at other times. The initial circuit to the magnet 16 is traceable from the plug socket 25, connection to socket 27, thence through the appropriate wire 34 to socket 22, plug connection 22a, to socket 20 28 and to magnet 16, and thence through commutator 35 to line 33. In this manner, in any column in which a socket 25 is plug connected to a magnet 16 and also to a corresponding magnet 19, the former will receive all impulses 25 through perforations in all index point positions and the latter will receive impulses through the 0, 11, and 12 index point position only.

It will be observed that in those columns in which numerical listing is desired, it is only necessary to connect the magnets 16. In the columns in which alphabetic listing is desired, both magnets 16 and 19 are plug connected.

In the foregoing, only so much of the operation of the printing mechanism as is necessary for an understanding of the present invention has been described and for further details of construction and operation, reference may be had to the aforementioned patent.

The features involved in the present invention will now be set forth. In Fig. 2 are shown the upper brushes UB which the record card passes exactly one machine cycle before it passes the lower brushes LB. These upper brushes terminate in plug sockets 36 and five such sockets 45 are shown connected in the diagram. In order to minimize the duplication of similar devices in the circuit, the arrangement is shown as limited to the handling of a five column field for one name and a four column field for the second name, and it will be understood that for fields of greater magnitude, additional devices, similar to those about to be described, may be provided. In Fig. 2, the five sockets 36 related to the brushes which read the five columns in the 55 "Surname" field are connected by plug connections 37 to sockets 38. As the card moves by the upper brushes UB, circuits will be completed in those columns in which a perforation appears. Such circuit may be traced from line 60 21, through cam contacts 38a which control the flow of current to the upper brush contact roller 38, through the uppermost brush UB, for example, socket 36, connection 37, socket 38, wire 40, a relay 1A, upper card lever contacts UCL, 65 cam contacts T1, to line 33.

The contacts UCL are closed by the presence of a card at the upper analyzing station and the contacts T1 are closed while the card is between the brushes and their cooperating contact roller. Magnet 1A will close its contacts 1A1 and 1A2, the former providing a holding circuit which extends from line 33, contacts T1, UCL, magnet 1A, contacts 1A1, wire 41, to line 70 21. The closure of contacts 1A2 establishes a 75

circuit traceable from line 33, through normally closed contacts T2, relay magnet 1B, contacts 1A2, cam contacts T3, wire 41, to line 21.

Referring to Fig. 6, it will be seen that the circuit just traced is not completed until contacts T3 close near the end of the cycle and that the circuit through the magnet 1A is maintained by the contacts T4 until the second circuit is completed. Upon completion of this second circuit, the contacts 1B1 are closed, providing a holding circuit for the magnet 1B from line 33, contacts T2, magnet 1B, contacts 1B1, wire 41, to line 21, which is held by the contacts T2 throughout the next following cycle during which the card passes the lower brushes LB. At the end of the cycle, the holding circuit for the magnet 1A is released, thus permitting its re-energization during the next cycle in response to a perforation in the next following card.

In the same manner, if a perforation were sensed by the second brush UB from the top, a circuit therethrough would energize relay magnet 2A and through its contacts 2A2 would cause energization of relay magnet 2B and the consequent holding circuit through contacts 2B1.

Likewise, a perforation in the third position will energize magnets 3A and 3B; in the fourth position, magnets 4A and 4B; and in the fifth position, magnets 5A and 5B. If the name sensed is a five position name, all of the magnets will be energized and if of less than five positions, the number of pairs of magnets will equal the number of places in the name sensed.

Each of the B magnets controls a group of contacts comprising, for example in the 1B group, normally closed contacts 1Ba and normally open contacts 1Bb, which upon energization of their controlling magnet will be shifted.

The plug sockets 25 associated with the lower brushes LB which sense the "Surname" field are connected through plug connections 42 to sockets 21 associated with the type bar printing magnets in the position in which the surname is to be printed. This manner of connection is effected when the arrangement of printing is to be in accordance with the example of Fig. 4. The brushes which traverse the "First name" field have their sockets 25 connected through plug connections 43 with plug sockets 44. As the card proceeds past the lower brushes, the print control magnets 16 and 18 will be controlled in the same manner as explained in the Gray patent. The controlling circuits are traceable from line 21 through cam contacts T4, T5, LCL, distributor 23, brush LB, socket 25, connection 42, socket 21, wire 34, to magnet 16 and line 33 for the initial energization of the magnet. The circuit will thereafter branch, in response to the second perforation, through wires 28, brushes 29, wires 31, to magnets 18 for the final selection of the character to be printed.

The circuits for the characters in the "First name" field are to be shifted so that the first letter is printed at a single-space interval from the last letter of the surname. This manner of shifting may best be explained by tracing a specific example, for instance, that indicated on the circuit diagram where the surname "DOE" is to be followed by the first letter "A" of the "First name". The circuit is traceable from the brush LB which senses the letter "A" through connection 43 to the uppermost socket 44, thence through the line 45 which is accented by a heavy line, thence through (now

closed) contacts 3Bb, closed as explained above, due to the energization of its controlling magnet 3B, thence through contact 4Ba, which is in closed position since its magnet 4B has not been energized, there being only three letters in the "Surname", wire 46, to socket 22 and connection 22a to socket 26, and thence branching to the magnets 16, 18 to select the character "A" for printing. By examining the circuit connections, it will be found that the letter "D" is connected to control a definite pair of magnets 16, 18, the letter "O" to the next adjacent, the letter "E" to the third, and the letter "A" to the fifth, thus providing for a blank space in which no printing is effected between the last letter of the surname and the letter "A".

It will also be observed that if the surname had contained only two letters, only the 1B and 2B magnets and their related contacts would have been operated and the circuit extending through wire 45 would have continued upwardly to go through contacts 2Bb, thence through contacts 3Ba, and through the next adjacent wire 46 to control printing in the fourth position magnets 16 and 18, thus maintaining the single-space relationship between the two.

By following out the circuit connections for the letters following the first name of each of the names, it will be apparent that they control selection of type bars in proper order.

Where the arrangement of printing is to be reversed, as for the example of Fig. 5, plug connections 37 in Fig. 2 are made to the sockets 36 which are connected to the brushes reading the "First name" field and the connections 42 are made from the sockets 21 to the sockets 25 which read the same field. The sockets 44 are connected to the sockets 26 associated with the "Surname" field and this transposition of plug connections is sufficient to effect the printing in the form of Fig. 5.

To take care of the condition in which a surname or a first name contains a space, each of the 1A magnets is provided with an extra set of contacts, for example 2A3, 3A3, 4A3, etc., so that the occurrence of a perforation in the third letter position may energize, as explained above, the magnet 3A and the closure of the contacts 3A3 will complete a circuit which is traceable from line 21, wire 41, through contacts 3A1, contacts 3A3, and thence through magnet 2A, contacts UCL, and T4, to line 33. Thus, if the magnet 2A has not been closed in response to the presence of a perforation in its related order, the presence of a perforation in the next order will serve to energize the magnet. In this manner the number of pairs of elements A and B which are energized is equal to the number of columnar positions of the record card field to be utilized in recording the name, including spaces or where in a card field of the "First name" there is also recorded a middle initial.

It will be understood that the application of the invention is not limited to the printing of names or other alphabetic designations but may be applied to the printing of code numbers or other symbols, and it is apparent that the arrangement may be such that the spacing may be any desired extent.

While there has been shown and described and pointed out the fundamental novel features of the invention as applied to a single modification, it will be understood that various omissions and substitutions and changes in the form and de-

tails of the device illustrated and in its operation may be made by those skilled in the art without departing from the spirit of the invention. It is the intention therefore to be limited only as indicated by the scope of the following claims.

What is claimed is as follows:

- 5 1. In a printing mechanism of the class described, means for sensing a plurality of separate record card fields for perforations contained in a variable number of columns in each field, printing mechanism controlled by said sensing means for printing characters represented by said perforations and further means controlled by said sensing means for causing the characters printed from the separate fields to be printed with a definite predetermined space relationship between them.
- 10 2. In a printing mechanism of the class described, means for sensing a pair of record fields of fixed extent, one containing perforations representing a surname and the other a first name, said names being of variable length, printing mechanism controlled by said sensing means for printing said names and further means controlled by said sensing means for causing the surname and first name to be printed with a predetermined spacing between them.
- 15 3. In a printing mechanism of the class described, means for sensing a pair of record fields of fixed extent, one containing perforations representing a surname and the other a first name, said names being of variable length and the letters thereof being perforated in non-adjacent columns of their respective fields, printing mech-

anism controlled by said sensing means for printing said names, and further means controlled by said sensing means for causing the surname and first name to be printed with the same relative space relationship as in their respective fields but with a predetermined spacing between the two names.

4. In a machine of the class described, a plurality of analyzing devices for sensing a field of a record card for perforations contained in the 10 columns thereof, a plurality of printing devices, an operating connection between each analyzing device and one of said printing devices, means for sensing a second field of the record card and means controlled thereby effecting a variable 15 shifting of the arrangement of the connections between said analyzing and printing devices.

5. In a printing mechanism, means for sensing a record column of a card, further means for sensing a plurality of columns of a field of said 20 card, means controlled by said field sensing means for determining the number of columns of said field containing perforations, a plurality of printing devices and means controlled by said determining means for selectively connecting said 25 column sensing means to one of said printing devices in accordance with the number of columns of said field having perforations.

6. The invention set forth in claim 5 in which said determining means includes a plurality of 30 relays there being one for each column of the field sensed.

JAMES W. BRYCE.
